UNITED STATES PATENT OFFICE.

CHARLES J. SOSS, OF NEW YORK, N. Y., ASSIGNOR OF ONE-FOURTH TO JOSEPH SOSS,
ONE-FOURTH TO HENRY SOSS, AND ONE-FOURTH TO SAMUEL SOSS, ALL OF NEW
YORK, N. Y.

HINGE.

1,402,103.

Specification of Letters Patent. Patented Jan. 3, 1922.

Application filed June 25, 1921. Serial No. 480,259.

To all whom it may concern:

Be it known that I, CHARLES J. Soss, a citizen of the United States, and residing at New York, in the County of New York and State of New York, have invented certain new and useful Improvements in Hinges, of which the following is a specification, such as will enable those skilled in the art to which it appertains to make and use the same.

This invention relates to hinges or hinge butts and particularly to articles of this class made from a single piece of metal, and the object of the invention is to provide an improved hinge butt which is formed from a sheet metal blank fashioned to produce a complete hinge butt which will possess the greatest possible strength and durability, and which may be manufactured at a minimum expense, and with this and other objects in view the invention consists in a hinge butt of the class specified and the method of producing the same, as herein-after described and claimed.

The invention is fully disclosed in the following specification, of which the accompanying drawing forms a part, in which the separate parts of my improvement are designated by suitable reference characters in each of the views, and in which:

Fig. 1 is a plan view of a blank from which one form of my improved hinge butt is made;

Fig. 2 a side edge view of the blank shown in Fig. 1 and illustrating the first step in the method of producing a hinge butt;

Fig. 3 a view showing the second step in the formation of the hinge butt;

Fig. 4 a view showing the third step;

Fig. 5 a partial section on the line 5—5 of Fig. 4 and showing the last step and forming the complete hinge butt;

Fig. 6 a partial section on the line 6—6 of Fig. 5, but showing a slight modification;

Fig. 7 a partial section on the line 7—7 of Fig. 5 and showing another modification;

Fig. 8 a partial section on the line 8—8 of Fig. 7 and showing a modification;

Fig. 9 a view similar to Fig. 1 showing a modified form of blank; and,

Fig. 10 a perspective of the complete hinge butt formed from the blank shown in Fig. 9.

In Figs. 1 to 5 inclusive, I have shown one form of construction and have indicated the principal steps in the formation of said hinge butt, and in Fig. 1 I have shown at 11 a blank from which the hinge butt is formed, and said blank is provided at one end with an oblong rectangular end portion 12 which forms the attaching plate 13 of the hinge butt, and this plate is provided with a plurality of apertures 14, and centrally thereof with two elongated apertures 15.

Joining the end portion 12 of the blank is a comparatively wide body portion 16 provided adjacent to said end with laterally projecting curved members 17. The blank 11 is split or cut as shown at 18 to separate said members 17 from the end 12 up to the dot and dash lines 19 upon which the blank is folded, as hereinafter set out. The body 16 is provided at its other end with a slightly reduced portion 20 outwardly of which is a reduced extension 21 having an enlarged fork-shaped head 22, said head being formed by a central recess 23 and projecting members 24.

In the operation of forming the hinge butt from the blank 11 fashioned as above set out, said blank is first folded upon the transverse line 25 to form a tubular knuckle 26 of the extension 20 of said blank and in folding the blank, as above set out, the reduced end portion 21 is placed upon the enlarged portion 16 of the blank, as clearly shown in Fig. 2, and the parts thus folded may be spot welded together, if desired.

The next step in forming the complete hinge butt consists in folding or bending the blank, or the enlarged portion 16 thereof on the lines 19 to provide flanges 27 at the opposite sides of the portion 16 of the blank, and the members 17 at right angles to the body of the blank and to overlap the side edge portions of the extension 21, as shown at 28 in Figs. 3 and 5 of the drawing. In this operation, the fork-shaped head 22 on 95 the end of the extension 21 is also folded on the lines 30 of Fig. 1 so as to bring the projecting members 24 and the curved rear portions 31 thereof at right angles to the body of the blank as shown at 32 in Figs. 3 100 and 5 of the drawing.

The next operation consists in bending the portion 16 of the blank as formed in

- Fig. 3 on the line 33 of Fig. 1 to form a hook-shaped arm 34 as shown in Fig. 4, and the rectangular end portion 12 of the blank is also bent at right angles, or approximately so, in this operation, and the projecting members 24 pass through the apertures 15 as shown at 35 in Fig. 4 in the above operation of bending the end portion 12, as above set out.
- 10 The next operation consists in heading or riveting that portion of the members 24 which projects through the plate 13 of the hinge butt formed by the rectangular end portion 12 as shown at 36 in Fig. 5, and this securely locks the plate 13 in connection with the end portion 21 and holds the various portions of the hinge butt together, and it will be noted that the projecting members 17 abut against the inner face of the plate 13 to reinforce said plate and the hinge butt member when completely formed. It will also be apparent that the hinge butt when completely formed may be welded at predetermined points, if desired, and the complete hinge butt finished to the desired dimensions by means of suitable forming dies.
- 15 From the foregoing it will be apparent that I produce a hinge butt comprising an attaching plate, a hook-shaped arm having a bearing for the usual pivot pin at its free end portion, which hinge butt by reason of the method of forming the same will possess the greatest possible strength and may be made at a minimum of expense.
- 20 In Fig. 6 of the drawing I have shown a slight modification of the construction shown in Figs. 1 to 5 inclusive, in which the reduced extension 21, or the central portion thereof, is extended to a slight extent, and the extended portion is bent as shown at 37 in said figure to reinforce that part of the hinge butt which integrally joins the plate 13, formed by the head 12, with the hook member 34 or the parts 16 thereof, and this extension will serve to reinforce and strengthen the said corner portion of the hinge butt.
- 25 In Fig. 7 I have shown another slight modification of the construction shown in Figs. 1 to 5 inclusive, in which the central portion of the attaching plate 13, or that portion thereof provided with the apertures 15 is pressed inwardly to form a recess 38 on the outer face thereof, and into which the projecting material of the members 24 may be pressed in the riveting operation above set out to form a smooth or flush outer face for said attaching plate.
- 30 In Fig. 8 of the drawing, I have shown another modification in which the projecting members 24 are riveted into the recess 38 as shown in Fig. 7, but in this figure I also show the members 17 as provided with projecting members similar to the members 24,

and which are riveted as shown at 39 into the recess 38, and these projecting members will be cut from a blank in the manner illustrated in Fig. 9 of the drawing.

In Fig. 9 of the drawing a modified form of blank is shown, and it will be noted that the blank shown in this figure is not provided with the fork-shaped head 22 on the reduced extension 21, and the members 17 are provided at their outer ends with projecting members 40 cut from the rectangular end 12 of the blank as shown in said figure, and said members are adapted to pass through the apertures 15 in the end portion 12 which constitutes the attaching plate 13 of the hinge butt in forming the complete hinge butt from the blank shown in Fig. 9, and the result of this operation is shown in Fig. 10 of the drawing.

It will be understood that the hinge butt shown in Fig. 10 and formed from the blank shown in Fig. 9 will be made in accordance with the steps of the process hereinbefore described relative to Figs. 1 to 5 inclusive, but instead of passing the projecting members 24 through the plate 13 the projecting members 40 are passed through said plate, or the apertures 15 therein, it being apparent that said apertures in the last named case are spaced further apart than the apertures 15 in the blank shown in Fig. 1.

My invention is not limited to the specific method of forming the hinge butts herein shown and described, nor to the specific form and construction thereof, and various changes therein and modifications thereof, may be made, within the scope of the appended claims, without departing from the spirit of my invention or sacrificing its advantages.

Having fully described my invention, what I claim as new and desire to secure by Letters Patent, is:

1. A hinge butt composed of a single piece of sheet metal fashioned to form an attaching plate and a hook-shaped arm extending therefrom, and parts of said arm being passed through and secured to said plate.

2. A hinge butt fashioned from a sheet metal blank, said blank being bent approximately centrally thereof to form a hook-shaped arm composed of two thicknesses of the material of said blank, the arm being provided at one end with a tubular knuckle and at the other end with an attaching plate, and means on said arm adapted to be passed through and secured to said attaching plate, for reinforcing and strengthening said plate.

3. A hinge butt fashioned from a sheet metal blank, said blank being bent approximately centrally thereof to form a hook-shaped arm composed of two parts of the material of said blank, said arm being provided at one end with a tubular knuckle and at the

other end with an attaching plate, and one of the parts of said arm being bent over the side edge portions of the other part.

4. A hinge butt fashioned from a sheet metal blank, said blank being bent approximately centrally thereof to form a hook-shaped arm composed of two parts of the material of said blank, said arm being provided at one end with a tubular knuckle and 10 at the other end with an attaching plate, one of the parts of said hook-shaped arm being of greater width than the other to form flanges which are bent over the side edge portions of the other part, and said 15 flanges being provided with parts adapted to be passed through and secured to said attaching plate.
5. A hinge butt of the class described comprising an attaching plate, a hook-shaped 20 arm composed of separate parts one of the parts of said arm being provided with flanges which overlap the side edge portions of the other part, and said flanges being provided with parts which extend 25 through and are secured to said attaching plate.
6. A hinge butt of the class described comprising an attaching plate, a hook-shaped

arm composed of separate parts one of the parts of said arm being provided with 30 flanges which overlap the side edge portions of the other part, said flanges being provided with parts which extend through and are secured to said attaching plate, and the other part of said arm being provided 35 with members which pass through and are secured to said attaching plate.

7. A hinge butt of the class described comprising an attaching plate, a hook-shaped arm composed of separate integrally 40 connected parts, one of the parts of said arm being provided with flanges which overlap the side edge portions of the other part, and means on said hook-shaped arm passed through and secured to said attaching plate for reinforcing and strengthening 45 said attaching plate and said arm.

In testimony that I claim the foregoing as my invention I have signed my name in presence of the subscribing witnesses this 50 23rd day of June, 1921.

CHARLES J. SOSS.
